UNITED STATES PATENT OFFICE.

JOHN G. STOLLER, RICHARD L. MILLER, AND WILLIAM Y. BEAN, OF ST. LOUIS, MISSOURI.

RAILWAY FREIGHT-CAR.

SPECIFICATION forming part of Letters Patent No. 764,390, dated July 5, 1904.

Application filed August 3, 1903. Serial No. 168,023. (No model.)

To all whom it may concern:

Be it known that we, JOHN G. STOLLER, RICHARD L. MILLER, and WILLIAM Y. BEAN, citizens of the United States, all residing at 5 the city of St. Louis and State of Missouri, have jointly invented a new and useful Railway Freight-Car, of which the following is a specification.

Our invention relates to improvements in 10 railway freight-cars wherein provision is made to transport oil or other liquid as freight in bulk together with general merchandise and all occupying the same vertical area of car-space and covering the features of adaptability of a box or platform car with a tank-car; and the objects of our improvements are, first, to provide a car having a lower metal tank-body and an upper platform or base for 15 a box or platform car part formed of or upon the upper or top of the tank and in combination therewith; second, provide enlarged carrying capacity of a freight-car and reduce the traction incident to its movement upon the rails by deflecting the center of gravity below 20 the perimeter of the truck-wheels; third, provide a combination-body to a freight-car that will be susceptible of being carried on the ordinary car-trucks without change therein.

In the drawings, Figure 1 is a side elevation 25 of our improved car, showing its general configuration and operation. Fig. 2 is a vertical cross-sectional view on line A A, Fig. 1. Fig. 3 is a vertical cross-section view through the middle of the car, showing parts and 30 method for loading and unloading the tank-section of the car; and Fig. 4, a vertical cross-sectional view on line C C, Fig. 1, showing form and connections over car-trucks.

Similar figures designate similar parts 35 throughout the several views.

In the drawings, 1 represents the body of a box-car; 2, the tank; 3, the trucks; 4, the car-bolster, which may be of the ordinary T-bar iron or other form or material for that purpose; 5, the truck-bolster, formed of channel-bars or hollow castings; 6, the king-bolt and openings to connect and hold the car-body to the trucks; 7, the girder-frame; 8, stiffening-angles to web of girder-frame 7 to take up

shear and prevent buckling of the girder under stress vertically; 9, saddle of tank connected on each side of car-girder 7 by vertical and angle connections 8, also to take up and guard against lateral buckling of girders under concussion and the like. 50

10 is the semi-annular body or holder of the tank; 11, receiving and discharge pumps with screw-caps for opening and closing same; 12, section of hose or pipe used in filling or discharging tank; 13, manhole for entering tank 60 to gage or repair same; 14, I-beams transverse to girders and over tank-supporting floor or platform of car and bracing upper flanges of girders; 15, nailing-strip secured in I-beam upon which to fasten superstructure of the 65 car-body.

The advantages which our hereinabove construction in a combination railway freight-car offer are found in utilizing the space between the forward and rear trucks for carrying purposes, and thereby settling the load to a lower plane of gravity, whereby there is brought about a saving in the power necessary to be expended in moving an equal weight situated higher up above the periphery of the wheels 70 of the trucks, as in other constructions. Besides facilitating the motion of the car our invention provides a wider range of usefulness in transportation of oil or other liquid articles in substantially the same car-body 75 with general merchandise and susceptible of being carried on the ordinary wheel-trucks without material change.

Having thus described our invention, that which we claim as new, and desire to secure 80 by Letters Patent, is—

1. In combination with the trucks of a freight-car, a semi-annular tank formed of a series of deflected semi-annular supports connected transversely to the girder sides, stiffening for the girder-frame, angle connections joining the saddle of the tank on each side to the car-girder, the said tank having a depending central part between the trucks substantially as described. 90

2. The combination with a freight-car body of a semi-annular tank located upon a saddle formed of a series of deflected semi-annular

supports connected transversely to the girder sides, such tank having a deeper central part between the car-truck wheels than at the ends, all substantially as shown and described and 5 for the purposes set forth.

3. The combination in a body of a railway freight-car of a base-girder having stiffening-angles supporting its web, and provided with a saddle carrying a semi-annular tank together 10 with transverse I-bars for platform-base of upper part of the car over top of tank and a

platform supporting and forming part of a box-car, or without a box as desired, all substantially as shown and described and for the purposes specified.

JOHN G. STOLLER.
RICHARD L. MILLER.
WILLIAM Y. BEAN.
